UNITED STATES PATENT OFFICE.

WILLARD J. HIELD, OF MINNEAPOLIS, MINNESOTA.

STREET-CAR GATE.

SPECIFICATION forming part of Letters Patent No. 546,116, dated September 10, 1895.

Application filed December 31, 1894. Serial No. 533,442. (No model.)

To all whom it may concern:

Be it known that I, WILLARD J. HIELD, a citizen of the United States, residing at Minneapolis, in the county of Hennepin and State 5 of Minnesota, have invented certain new and useful Improvements in Street-Car Gates; and I do hereby declare the following to be a full, clear, and exact description of the invention, such as will enable others skilled in the 10 art to which it appertains to make and use the same.

My invention is especially designed for electric street-railway cars, although capable of use on other kinds of cars, and has for its 15 object to provide a convenient and reliable gate for controlling the entrance to or exit from the car.

To this end my invention consists in the novel devices and novel combinations of 20 devices hereinafter fully described, and defined in the claims.

The accompanying drawings illustrate my invention, wherein like letters refer to like parts.

25 Figure 1 represents in side elevation an electric street-railway car equipped with my improvement, some parts being broken away for better showing the construction. Fig. 2 is a horizontal section approximately on the 30 line X X of Fig. 1, with some parts broken away; and Fig. 3 is a skeleton view, in perspective, showing the gates and the lever connections for controlling the same for the most part detached from their supports.

35 a a' a^2 a^3 represent, respectively, the body portion, the front-end vestibule, the rear-end platform, and the platform-steps of an ordinary street-railway car, such as are used in the electric systems in the Northwest. This 40 body is mounted on suitable trucks a^4 and truck-frame a^5 of the ordinary standard construction, and may either be equipped with an electric motor (not shown) for use as a motor-car or be a trailer, designed for connection to the motor-car. In all such cars, especially when equipped as motor-cars, the 45 motormen is provided with a front-end vestibule a' , partitioned off from the body of the car, and wherein the motormen constantly remains 50 when the car is in service, and therefrom controls the movements of the car. Such cars are usually arranged to receive passengers from

the rear end only, and on the double-track systems employed in all large cities are usually arranged to permit entrance and exit only from one side of the rear platform a^2 , or, otherwise stated, only a single set of steps a^3 are provided at the rear-end platform a^2 , which are located on what is known as the "outside" of the car. Great difficulty has been 60 experienced in controlling the entrance and exit of the passengers to and from the car. In spite of all precautions and care on the part of the conductor, passengers will persist in jumping on and off while the car is in motion. In consequence thereof accidents frequently occur with resulting large damage suits, in many instances, against the street-railway company or other proprietors of the street-railway. To meet these conditions and 65 overcome these objections I provide a double or two wing gate b b , the wings of which are preferably made of open or net-like wire work, fixed to upright posts b' and marginal strips b^2 . The posts b' are journaled below 70 in bearing-brackets b^3 , fixed to the lowermost of the steps a^3 , and are journaled above in bearing-brackets b^4 , one of which is fixed to the car-body and the other to the hand rail or guard of the platform.

75 The posts b' are provided near their lower ends with crank-arms b^5 fixed thereto, but located thereon so as to project in opposite directions. The said crank-arms b^5 are pivotally connected to the opposite ends of a common draw-bar b^6 , which in turn is connected 80 at its forward end to a draw-rod b^7 , which extends forward under the car-body, as shown in dotted lines in Fig. 2, and is pivotally attached at its forward end to a crank-arm b^8 85 fixed to the lower end of a hand-shaft b^9 b^{10} . The lower end of the shaft b^9 has its bearing in a bracket b^{11} , which is bolted to two sills a^6 of the motormen's platform a^7 in the vestibule a' . The upper end of the shaft b^9 has 90 its bearing in a hub of a two-arm bracket b^{12} , the arms of which are bolted to the side posts a^8 or other fixed parts of the vestibule a' . The forward end of the draw-rod b^7 is curved, as best shown in Figs. 2 and 3, so as to permit the parts to assume the position shown in 95 the several views. The draw-rod b^7 may work through one or more suitable keepers b^{13} fixed to the car-body. The crank-arms b^5 on the 100

gate-wing posts b' are of greater length than the crank-arm b^8 on the hand-shaft b^9 . Hence the hand-shaft b^9 and the crank-arm b^8 will have to move through a greater number of 5 degrees than the crank-arms b^5 and the posts b' in throwing the gate-wings from their closed to their open position, or vice versa. The parts are proportioned to throw the gate-wings through a little more than a quarter of 10 a circle, and the relative proportions of the crank-arms b^5 and the crank-arm b^8 are such that to accomplish this result the hand-shaft b^9 and the crank-arm b^8 will move through a little more than a half-circle. Otherwise 15 stated, the crank-arm b^8 throws past the center in each direction, and is thereby made to lock the gates either in their closed or in their open position. In Fig. 1 all the parts are 20 shown as they would appear when the gate-wings are closed, and the same is true of the parts shown in Fig. 3. In Fig. 2 all the parts are shown as they would appear when the gate-wings are open.

From the foregoing statements it must be 25 obvious that the gate is entirely and solely under the control of the motorneer in his vestibule a' , and that the gates cannot be opened until the motorneer sees fit to operate his gate-lever b^{10} . The entrance and exit of the 30 passengers to the car is therefore solely and entirely under the control of the motorneer only. Hence, entrance and exit need only to be possible when the car is at rest. The advantages of such an arrangement have already 35 been pointed out.

It will, of course, be understood that while I have shown and described the gate as composed of a pair of wings that this gate might take various forms. For example, the gate 40 might be composed of a single wing, or it might be in the form of a sliding bar or folding gate. In other words, any form of a gate which is provided with operating connections which extend to the motorneer's platform 45 would be within the scope of my invention.

What I claim, and desire to secure by Letters Patent of the United States, is as follows:

1. The combination with a car body, of a gate controlling the entrance thereto, and lever connections for operating said gate, ar-

ranged automatically and positively to lock the same in one of its extreme positions, under the action of moving the gate, substantially as described.

2. The combination with a car body, having a rear end passenger entrance and a front end platform for the motorneer, or car operator, of a two-winged gate controlling said rear end entrance, and lever connections for operating said gate, extending to the motorneer's platform, said operating connections being arranged automatically and positively to lock the wings of said gate both in their open and closed positions, under the action of moving the same, substantially as described. 55

3. The combination with the car-body, of a gate controlling the entrance thereto, a draw-bar having connections to said gate, at one end, and a hand operated crank-shaft at the other end of the said draw-bar, having a crank-arm connection thereto, which crank-arm is arranged to be thrown, in the act of moving the gate, to and from a dead center, whereby said gate when moved to its closed 70 position will be automatically locked, substantially as described. 75

4. The combination with a car body, having a rear end platform, for the entrance or exit of passengers, and a front end platform 80 for the car operator, of a two-wing gate closing the entrance to said rear platform, a draw-bar connected to crank arms on the pivot-posts of said gate-wings, a draw-bar extending forward from said connecting bar to a hand shaft on the operator's platform, and a crank arm on said shaft connected to said draw-bar, which crank arm is of less length than the crank arms on said gate-wing posts, whereby the hand-shaft crank will be thrown 90 by the dead center either to open or to close the gate-wings, and will thereby lock the gate-wings in their open or closed positions, substantially as described.

In testimony whereof I affix my signature 95 in presence of two witnesses.

WILLARD J. HIELD.
